UNITED STATES PATENT OFFICE.

JOSEPH MARTIN TRACY, OF SEATTLE, WASHINGTON.

SPRING-BENDING MACHINE.

1,260,733.

Specification of Letters Patent. Patented Mar. 26, 1918.

Application filed July 17, 1916. Serial No. 109,716.

To all whom it may concern:

Be it known that I, JOSEPH MARTIN TRACY, a citizen of the United States, and a resident of Seattle, in the county of King and State 5 of Washington, have invented certain new and useful Improvements in Spring-Bending Machines, of which the following is a full, true, and exact specification.

My invention relates to improvements in 10 spring bending machines, and has for its principal object to provide an improved and novel device for bending the various leaves of a leaf spring to any predetermined shape; to provide a device of the class described in 15 which the first leaf bent is used as a form against which the next leaf upon either side of it may be bent and in which the last leaf bent in any particular spring is used as the form for the adjacent leaf. Another object 20 of my device is to provide adjustable means for bending the leaves of the spring to the desired shape. In the bending of leaves for a leaf spring it is necessary that each leaf be bent so as to bear against the leaves upon 25 either side of it in such a manner as to develop the resistance of all the leaves of the spring to their proper proportion. The usual method of bending is by means of hand tongs which is manifestly slow and in- 30 accurate and a large amount of time is consumed in the bending which allows the hot leaf to cool and it is frequently necessary to reheat the leaf before quenching. While it is known to applicant that there are other 35 spring bending machines in which adjustable keyboards and a multiplicity of patterns are used, no device is known in which each leaf of a given spring is in turn used as a form against which to bend the adjacent 40 leaves. Applicant's device is easily operated by one man and forms the leaf quickly and accurately so that no time is lost in quenching and further, any desired shape of spring may be built up without patterns 45 by simply forming the first leaf to a predetermined shape and forming the subsequent leaves by using those already bent as a form.

Other objects will appear as my invention 50 is more fully explained in the following specification, illustrated in the accompanying drawings and pointed out in the appended claims.

In the drawings Figure 1 is a front elevation of my device. Fig. 2 is a side elevation of same. Fig. 3 is an enlarged de-

tail view illustrating applicant's clamping means. Fig. 4 is another view of the mechanism.

Referring more particularly to the drawings, numeral 1 indicates a base upon which my device is mounted. Secured to base 1 is a vertical mast 2 upon which a carrier 3 is slidably mounted. A pair of similar plunger frames 4 are pivoted as at 5 adjacent the lower end of carrier 3. The upper edges of frames 4 are retained in proper alignment by guide 6. Carrier 3 is suspended from a cross arm 7 by means of spring 8. The outer ends of frames 4 are 60 similarly supported by means of springs 9. Plungers 10 are mounted vertically in openings in the upper and lower members of frames 4 and are clamped in position by means of clamp rods 11, hand screws 12 and 65 fillers 13. The plungers 10 may be adjusted vertically in either frame by simply loosening the hand screws 12 and shoving the plungers up or down as the case may be. A yoke 14 is slidably mounted upon mast 2 70 and is suspended from the outer ends of frames 4 by means of adjustable tie rods 15 and centrally from carrier 3 by means of a 75 spring 16. Any suitable lever arrangement may be used to draw downwardly the yoke 80 14, frames 4 and carrier 3. Such a lever arrangement may consist of a hand or foot lever 17 which is pivoted to yoke 14 as at 85 18 and the inner end of which is pivoted as at 19 to links 20 which in turn are pivoted 90 to bearings 21 which are mounted upon base 1. An anvil 22 is secured to mast 2 at a point somewhat below the normal position 95 of carrier 3. An intermediate cross arm 23 is also secured to mast 2 below anvil 22. 100 Adjustable and resilient spring leaf supports are slidably mounted adjacent either end of intermediate cross arm 23. The spring end supports include vertically adjustable bolts 24 which are slidably horizontally in slots in the intermediate cross arm 23. Coil springs 25 surround the bolts 24 and project above them. In operation the plungers 10 are set so that the lower ends contact with the line of a predetermined 105 spring curve somewhat as shown in Fig. 1. It will be noted in Fig. 1 that the carrier and plunger frames are somewhat pulled downwardly from the normal position in order to better illustrate the relationship of 110 the plungers and spring end supports. After the plungers have been properly set

the hot spring leaf is resting centrally upon anvil 22 and the ends of the spring allowed to evenly balance themselves upon the tops of springs 25. The lever 17 is then thrown 5 downwardly which pulls the yoke 14, carrier 3 and plunger frames 4 down along the mast 2. The lower ends of plungers 10 engage the leaf and bend it to the form of the curve of the plungers. After the plungers nearest 10 the mast grip the leaf against the anvil 22, the carrier and the inner ends of the frames are stopped from further vertical movement but the continued depression of the lever 14 continues to lower the outer ends of frames 15 4 which swing about pivot points 5. The outer ends of frames 4 are pulled down until the leaf engages the upper ends of bolts 24 which brings the frames to a stop. It will be understood that the presence of the springs 16 20 permits the yoke 14 to continue its downward movement after carrier 3 has come to a standstill. The device is now released and the form leaf is quickly quenched in an oil tempering bath from which it is immediately withdrawn and placed across the 25 anvil in readiness to be used as a form against which to bend a new leaf which is to lie adjacent to it in the finished spring. The new hot leaf is placed above the first 30 bent leaf which is now used as a form and the operations of bending the hot springs are repeated as previously stated excepting that no new adjustment is made in the plungers 10. The new leaf is bent down hard 35 against the form leaf and when released possesses enough elasticity to spring away from the form the proper amount to give the correct clearance between adjacent leaves of the spring. The second formed 40 leaf is now quenched and used as a form for the third leaf and so on until the entire

spring has been formed. The only adjusting necessary as the subsequent leaves are being formed, as they become either shorter or longer as the case may be, is that the 45 spring end support means are moved inwardly or outwardly along the intermediate cross arm 23. From the foregoing it is believed that the construction and operations of my device will be fully understood. 50

While I have shown a particular form of embodiment of my invention, I am aware that many minor changes therein will readily suggest themselves to others skilled in the art without departing from the spirit 55 and scope of the invention, and I therefore desire to avoid being limited to the exact form shown and described.

Having described my invention what I claim as new and desire to protect by Letters Patent, is—

1. In a device of the class described, the combination of a vertically slidable carrier, swingable plunger frames pivotally mounted upon said carrier, a plurality of vertical 65 plungers adjustably mounted upon said frames, and stationary with respect to said frames, a stationary leaf supporting anvil, and means for moving the said carrier and frames with respect to the said anvil, whereby a spring leaf may be bent about the anvil to conform to the outline of the points of the said plungers. 70

2. In a device of the class described, the combination of a vertically slidable carrier, 75 swingable plunger frames mounted upon said carrier, a plurality of plungers adjustably mounted upon said frames, a stationary leaf supporting anvil, and adjustable resilient leaf supporting means, which are independent of said anvil. 80
